UNITED STATES PATENT OFFICE.

GEORGES ESTOPPEY, OF ORANGE, NEW JERSEY, ASSIGNOR TO MUSA, ESTOPPEY & CO.,
INC., OF NEW YORK, N. Y., A CORPORATION OF NEW YORK.

SPEED-INDICATOR.

1,296,641.

Specification of Letters Patent. Patented Mar. 11, 1919.

Application filed July 24, 1918. Serial No. 246,483.

To all whom it may concern:

Be it known that I, GEORGES ESTOPPEY, a citizen of Switzerland, residing at Orange, in the county of Essex and State of New Jersey, have invented Speed-Indicators, of which the following is a specification.

My invention relates to speed indicators and more particularly to a speed indicator adapted to be carried by an aeroplane or other such body moving above the earth to indicate the speed thereof relatively to the earth.

In view of the change in the speed and direction of the wind relatively to the earth and the aeroplane, there is a wide variation in the speed of the aeroplane relatively to the earth even when the aeroplane is traveling, as is usual, at a substantially constant speed relatively to the wind. It is the principal aim of my invention to provide speed indicating means which will give the speed of a body such as an aeroplane relatively to the earth regardless of the speed or direction of the wind.

Another object of the invention is to provide a device of the character referred to which is convenient to operate.

Another object is to provide a device for the purpose stated which has as an operative part thereof timing mechanism arranged to be readily controlled and observed by the operator; other objects of my invention will appear more fully hereinafter.

A clear understanding of the invention can best be had by reference to the accompanying drawings showing sighting apparatus embodying the invention in the form now considered best and illustrating the operation of said apparatus. In said drawings:

Fig. 1 is a side elevation partly broken away of the said form of the invention.

Fig. 2 is a section taken on line 2—2 of Fig. 1.

Fig. 3 is a section taken on line 3—3 of Fig. 2.

Fig. 4 is a view of the sighting member and timing mechanism forming a part of the apparatus of Fig. 1 viewing Fig. 5 from the left.

Fig. 5 is a fragmentary sectional view taken on line 5—5 of Fig. 4 and showing the arrangement of the timing mechanism with respect to the sighting member; and

Fig. 6 is a diagram explaining the operation of the apparatus.

Referring to the drawings the numeral (1) designates a sighting tube which is connected, as by means of brackets (2), to the rear of a disk (4). The latter is rotatably mounted, as by the central pivot (5), upon the frame (6). The pivot (5) is rotatable in the frame and is provided with means such as the usual bolthead (7) situated in a recess in the disk (4) to cause it to rotate with said disk. Adjacent its forward end 60 the pivot (5) has secured thereto a rack (8) the teeth of which are arranged in the form of a sector and mesh with the teeth of a pinion (9) secured upon a rotatable arbor (10) which is supported at its opposite end portions in the frame (6) and in a dial plate (11) secured to the frame in front of the said pinion and rack. The radius of the rack (8) is desirably longer than the radius of the pinion (9) so that for a given amount of rotation of the sighting tube (1) and the disk (4), the pointer (12) which is carried by the forward end of the shaft (10) in front of the dial (11) travels through a greater arc 70 than the sighting tube. The disk (4) and sighting tube carried thereby are rotated about the axis of the pivot (5) by suitable means such as crank (14) rotatably supported, as by pivot (15), upon the frame (6). The said pivot (15) has secured upon 75 the same a pinion (16) which meshes with the toothed periphery portion with the disk (4) as clearly shown in Fig. 3 in which only a portion of the teeth upon the periphery (4) are shown. The frame (6), as shown, is provided with a flange-like portion (17) 80 surrounding the peripheries of the disk (4) and pinion (16), said flange having secured to its outer edge portion a retaining ring (18) which is provided with an inwardly extending portion projecting inwardly over the rear face of the disk (4) adjacent the periphery of the latter. The frame (6) also has secured thereto a bracket (19) whereby the apparatus may be secured in proper position 85 upon an aeroplane or other body, the speed of which is to be measured. The frame (6) is also provided with a flange (20) which supports the dial (11) and surrounds the indicating mechanism in front of the body 90 portion of the frame (6). A front wall (21) resting at its lower edge upon a bracket (19) and secured at its periphery to the flange (20) serves as a closure for the front of the 95 compartment containing the rack (8), pin- 100

110

ion (9) together with the indicating means operated thereby. The wall (21) is provided with a transparent window (22) to permit the ready observation of the dial (11) 5 and pointer (12).

In the operation of the device it is necessary for the operator to know when a certain predetermined interval of time has elapsed. In accordance with this invention 10 a suitable timing mechanism is so arranged that the operator may be advised of the elapse of this interval of time without discontinuing to sight along the sighting member. The latter, as shown, is in the form of 15 an ordinary sighting tube with usual cross-hairs at right angles to each other and intersecting in the optical axis or line of vision and with an eye piece (30) of rubber or any other suitable material. Intermediate 20 the ends of the sighting tube there is a diaphragm (31) which cuts out a portion of the field of the sighting tube. The timing mechanism shown comprises a stop watch (32), the operating mechanism of which 25 may be of usual construction. This stop watch is firmly held in position in a casing (33) which is mounted for axial rotation in a frame (34), the casing (33) being held against axial displacement from the frame 30 (34) by means of an annular rim (35) on the casing which projects into a recess in the front end of the frame (34), and by means of a ring (36) which is secured to the rear of the casing (33) and bears against the 35 rear of the frame (34). The frame (34) is secured to the tube (3) by means of suitable flanges, one of which is shown as (37). The frame (34) is provided with a suitable slot through which the operating stem (38) on 40 the stop watch (32) passes, this slot permitting the said watch to be rotated axially within the frame. The stop watch, as shown, is set down a short distance within the sighting tube, although the major portion thereof 45 extends above the said tube, as more fully shown in Figs. 4 and 5. The pointer or hand of the watch is of greater length than the radius of the frame (34) so that it projects beyond the said frame and can be seen 50 at its lower end in sighting through the sighting tube, when the said pointer or hand is at its lower position. The dial of the stop watch is desirably graduated so as to indicate in addition to heights of the aero- 55 plane from the ground time intervals corresponding to such heights, as will appear hereinafter. For example, in Fig. 4 the inner series of graduation are heights and the outer series of graduation are intervals 60 of time corresponding thereto.

Suitable means are desirably provided whereby the same member by which the rotation of the tube (1) is controlled also controls the starting of the stop watch. To 65 this end the crank (14) is provided with a

hub (44) which contains a portion (45) projecting outwardly away from the axis of rotation of the crank. The cam member (44) co-acts with a roller (46) supported in a bearing upon one end of a wire 70 (47) which extends through a rigid tubular covering (48), the wire (47) being provided at its opposite end with a member (49) which is arranged co-axially with the stop watch (32) and with a member (50) movable longitudinally in a guide in the frame (43) when the parts are in position preparatory to making an observation for setting the sighting tube. The upper end of the tube (48) may be secured as 80 by a suitable bracket (51) to a stationary part of the machine. The construction and arrangement of parts is such that the parts (49) and (50) are arranged adjacent each other when the sighting tube is in proper 85 position preparatory to making the observation referred to, but the member (50) is located downwardly away from the member (49) in all other positions of the sighting tube. Means such as the spring (52) may be 90 employed to yieldingly hold the wire (47) in position with the roller (46) bearing against the cam member (44). The inner end of the member (50) bears against the lower end of a lever (53) pivoted intermediate its ends at (54) and bearing at its upper end upon a bell crank lever (55) pivoted at (56) and having a forked outer end engaging a recess in the stem (38), so that when the member (50) is forced inwardly 95 100 the stem (38) will be forced downwardly to start the stop watch.

In operation, the crank (14) is first rotated so as to bring the pointer (12) to the "0" point of the corresponding scale when the axis or line of vision of the sighting member makes an angle "a" (see Fig. 6) with the vertical. The operator also determines the height of his machine as by a barometer or other suitable means and rotates the stop watch (32) until the fixed reference mark (80) upon the glass (42) registers with the graduation on the face of the stop watch corresponding to such height. During this adjustment the pointer or hand (38') of the stop watch is moved from its former vertical position of rest, shown in Fig. 4, in an anti-clockwise direction. The aviator upon reaching a certain point such as "B" (see Fig. 6) will sight a certain point "A". At the point "B" the operator traveling along the line "BB'" (see Fig. 6) starts turning the crank (14), causing the sighting tube to be moved about the axis of pivot (5) so as to continually maintain the point "A" in the line of vision of the sighting tube. As soon as the operator begins to rotate the crank (14) the projection (45) on the member (44) moves the wire (47) so as to cause the member (49) to shift member 110 115 120 125 130

(50) inwardly and through the levers (53) and (55) to force in the stem (38) of the stop watch to start the movement of the hand or pointer (38) from its adjusted position of rest in a clockwise direction. The rotation of the crank (14) is continued by the operator so as to maintain the point "A" in the line of vision or axis of the sighting tube (1) until the pointer (38) reaches a vertical position registering with the vertical cross-hair of the sighting tube. At this moment the crank has been rotated for a period of time corresponding to the time required for an object to drop to the ground from a height equal to that at which the aeroplane is traveling, and the rotation of the crank is immediately stopped. At this time the axis or line of vision of the sighting member (1) makes an angle "b" with the vertical, the machine having reached the point "B", it being assumed that for the small interval of time in question the aeroplane is maintained at a substantially constant height above the ground and is operated at a constant speed. The pointer (12) will now point to a graduation of the scale upon the dial (11) which gives the absolute speed of the aeroplane relatively to the ground or earth regardless of the speed or direction of the wind.

The theory upon which the apparatus operates will be clear by reference to the diagram shown in Fig. 6.

If V = the speed of the aeroplane relatively to the earth and t = the time it takes for the aeroplane to travel from B to B'. Then

$$40 \quad V = \frac{BB'}{t} \quad (1)$$

But

$$45 \quad \begin{aligned} \frac{BB'}{AB} &= \frac{\sin c}{\sin AB'B} \\ &= \frac{\sin c}{\sin (b+90^\circ)} \\ 50 \quad BB' &= AB \left(\frac{\sin c}{\sin (b+90^\circ)} \right) \\ &= \frac{H}{\cos a} \left(\frac{\sin c}{\sin (b+90^\circ)} \right) \quad (2) \end{aligned}$$

From (1) and (2)

$$55 \quad \begin{aligned} V &= \frac{H}{t} \left(\frac{\sin c}{\sin (b+90^\circ) (\cos a)} \right) \\ &= \frac{H}{t} \left(\frac{\sin c}{\sin (a-c+90^\circ) (\cos a)} \right) \quad (3) \end{aligned}$$

60 In order to simplify the readings on the indicator dial and to employ only one scale for all altitudes (H), I make $\frac{H}{t}$ constant.

Where H is expressed in meters and t in seconds, a suitable value of this constant is

100, which gives the values in the following table:

Altitudes in meters.	Time in seconds.	$\frac{H}{t}$	
100	1	100	70
200	2	100	
500	5	100	
1000	10	100	
2000	20	100	
3000	30	100	75

Under these conditions the only variable in equation (3) is angle c ; so that with the angular movement of the tube (1) during the passage of the aeroplane from B to B' known, the speed of the aeroplane can be computed and the graduations of the scale on dial (11) readily marked.

While I have shown and described the form of my invention which I now consider best, numerous modifications may be made in the apparatus shown without departing from my invention.

What I claim and desire to protect by Letters Patent of the United States is:

1. In apparatus of the class described for use on a moving body, such as an aeroplane, the combination of sighting means comprising a movable sighting member, and means operable by maintaining the line of vision of said means upon a certain point for a predetermined period of time to indicate directly the speed of the body relatively to the body containing the point.

2. In apparatus of the class described for use on a moving body, such as an aeroplane, the combination of sighting means comprising a member movable to change the direction of the line of vision to the vertical, and means operable by maintaining the line of vision of said sighting means upon a fixed point upon the earth for a predetermined period of time depending upon the height of the moving body above the earth to indicate the speed of the body relatively to the earth.

3. In apparatus of the class described for use on a moving body, such as an aeroplane, the combination of sighting means comprising a member movable to change the direction of the line of vision to the vertical, and means operable by maintaining the line of vision of said sighting means upon a fixed point upon the earth for a predetermined period of time depending upon the height of the moving body above the earth to indicate the speed of the body relatively to the earth, said indicating means including a scale member and index one of which is movable relatively to the other.

4. In apparatus of the class described for use on a moving body, such as an aeroplane, the combination of sighting means comprising a member movable to change the direction of the line of vision to the vertical, and means operable by maintaining the line of

- vision of said sighting means upon a fixed point upon the earth for a predetermined period of time depending upon the height of the moving body above the earth to indicate the speed of the body relatively to the earth, said indicating means comprising a scale member and index member and speed increasing means for transmitting the movement of said movable member to one of said last named members.
5. In apparatus of the class described for use on a moving body, such as an aeroplane, the combination of sighting means comprising a member movable to change the direction of the line of vision to the vertical, means operable by maintaining the line of vision of said sighting means upon a fixed point upon the earth for a predetermined period of time depending upon the height of the moving body above the earth to indicate the speed of the body relatively to the earth, and timing mechanism having time indicating means visible when sighting with said sighting means.
10. In apparatus of the class described for use on a moving body, such as an aeroplane, the combination of sighting means comprising a member movable to change the direction of the line of vision to the vertical, means operable by maintaining the line of vision of said sighting means upon a fixed point upon the earth for a predetermined period of time depending upon the height of the moving body above the earth to indicate the speed of the body relatively to the earth, and timing mechanism carried by said movable member and having an indicator arranged to travel in the field of said sighting means.
15. In apparatus of the class described for use on a moving body, such as an aeroplane, the combination of sighting means comprising a member movable to change the direction of the line of vision to the vertical, means operable by maintaining the line of vision of said sighting means upon a fixed point upon the earth for a predetermined period of time depending upon the height of the moving body above the earth to indicate the speed of the body relatively to the earth, and timing mechanism carried by said movable member and having an indicator arranged to travel in the field thereof, said sighting means having a reference mark for said indicator, and said timing mechanism being adjustable to set said indicator toward or away from said mark.
20. In apparatus of the class described for use on a moving body, such as an aeroplane, the combination of sighting means comprising a member movable to change the direction of the line of vision to the vertical, means operable by sighting a fixed point with said sighting means a predetermined period of time to indicate the speed of the

body relatively to the earth, timing mechanism having time indicating means visible when sighting with said sighting member, and means comprising a unitary operating member for moving said movable member and controlling the operation of said timing mechanism.

9. In apparatus of the class described for use on a moving body, such as an aeroplane, the combination of sighting means comprising a member movable to change the direction of the line of vision to the vertical, means operable by sighting a fixed point with said sighting means a predetermined period of time to indicate the speed of the body relatively to the earth, timing mechanism carried by said sighting means and means comprising a unitary operating member for moving said movable member and controlling the operation of said timing mechanism.

10. In apparatus of the class described, the combination of means comprising a movable sighting member for indicating the speed of a body, said means being operable by making an observation with said sighting member for a predetermined period of time, timing means and means comprising a unitary operating member for moving said sighting member and controlling the operation of said timing means.

11. In apparatus of the class described, the combination of means comprising a movable sighting member for indicating the speed of a body, timing means, and means comprising a unitary operating member for moving said sighting member and controlling the operation of said timing means.

12. In apparatus of the class described, the combination of means comprising a movable sighting member for indicating the speed of a body, said means being operable by making an observation with said sighting member for a predetermined period of time, and timing means mounted to be observable when sighting with said sighting member.

13. In apparatus of the class described for determining the relative speed between two bodies, the combination of sighting means adapted to be carried by one body and comprising a member movable to change the direction of the line of vision, and means operable by maintaining the line of vision of said sighting means upon a fixed point upon the other body for a predetermined period of time to indicate directly the relative speed between the bodies.

14. In apparatus of the class described for determining the relative speed between two bodies, the combination of sighting means adapted to be carried by one body and comprising a member movable to change the direction of the line of vision, and means operable by maintaining the line of vision of said sighting means upon a fixed

point upon the other body for a predetermined period of time to indicate directly the relative speed between the bodies, said indicating means including a member having a scale, an index, and means for producing a relative movement between said scale and index by the operation of said sighting means to indicate the said relative speed on said scale for various distances between said bodies.

15. In apparatus of the class described for use on a moving body, such as an aeroplane, the combination of sighting means comprising a member movable to change the direction of the line of vision to the vertical, and means operable by movement of said member to indicate directly the speed of the

body relatively to the earth, said indicating means including a member having a scale, an index, and means for producing a relative movement between said scale and index by the operation of said sighting means to indicate the said relative speed on said scale for various distances between said bodies. 20

16. In apparatus of the class described, 25 the combination of means comprising a movable sighting member for indicating the speed of a body, and timing means connected with said sighting member, and arranged to be observed by an operator when 30 sighting with said sighting member.

In testimony whereof I have signed my name to this specification.

GEORGES ESTOPPEY.
